[57] CLAIM

The ornamental design for a dessert dish or similar article, substantially as shown and described.

DESCRIPTION

FIG. 1 is an elevational view of a dessert dish or similar article showing my new design in the size and proportion of a parfait goblet;

FIG. 2 is a top view thereof;

FIG. 3 is a bottom view thereof;

FIG. 4 is a sectional view taken along line 4—4 of FIG. 2;

FIG. 5 is a developed plan view of the foot thereof;

FIG. 6 is a developed plan view of the upper body thereof;

FIG. 7 is a plan view of a dessert dish or similar article showing another form of my new design in the size and proportion of a sundae goblet;

FIG. 8 is a top view thereof;

FIG. 9 is a bottom view thereof;

FIG. 10 is a sectional view taken along line 10—10 of FIG. 8;

FIG. 11 is a developed plan view of the foot thereof;

FIG. 12 is a developed plan view of the upper body thereof.

The surface exterior decoration which would be visible through the bowl and stem in FIGS. 2, 3, 4, 8, 9 and 10, have been omitted therefrom for convenience of illustration.
